UNITED STATES PATENT OFFICE.

WILLIAM M. PFITZNER, OF BROOKLYN, NEW YORK.

DESIGN FOR A PLAQUE.

SPECIFICATION forming part of Design No. 17,216, dated March 29, 1887.

Application filed February 19, 1887. Serial No. 228,261. Term of patent 3½ years.

To all whom it may concern:

Be it known that I, WILLIAM M. PFITZNER, a citizen of the United States, residing at Brooklyn, in the county of Kings, State of New York, 5 have invented and produced a new and original Design for a Plaque, of which the following is a specification, reference being had to the accompanying drawings.

Figure 1 is a face view of my newly-designed 10 plaque. Fig. 2 is a section on line *x x*, Fig. 1.

The leading feature of this design consists of a plaque surrounded by a horseshoe-shaped border.

a is a plate, having inclined rim *b*, surrounded 15 by a scalloped circle, *c*. This circle is partly

inclosed by a horseshoe-shaped border, *d*, having an indented surface.

e f f are projections upon the border *d*, in imitation of the toe and heel calks, and also having indented surfaces. 20

What I claim is—

The design for a plaque, consisting of plate *a*, rim *b*, circle *c*, and horseshoe-shaped border *d*, having indented surface, and of indented calks *e f f*, substantially as shown.

WILLIAM M. PFITZNER.
